UNITED STATES PATENT OFFICE.

CHRISTIAN J. BERGLANN, OF SEATTLE, WASHINGTON.

SEINE-PULLER.

1,249,888.

Specification of Letters Patent. Patented Dec. 11, 1917.

Application filed May 9, 1917. Serial No. 167,606.

To all whom it may concern:

Be it known that I, CHRISTIAN J. BERGLANN, citizen of the United States, residing at Seattle, in the county of King and State 5 of Washington, have invented a certain new and useful Improvement in Seine-Pullers, of which the following is a specification.

My invention relates to improvements in seine pullers of that class employed on fishing vessels for pulling a seine from the water on to a vessel's deck and the object of my invention is to provide a seine puller which shall be securely fastened on a platform pivotally mounted in a socket fixed in 10 the deck of a vessel, and which shall be adapted to be operated evenly to pull a seine from the water on to said platform from any direction within an angular distance of ninety degrees from either side of the vessel's keel, and whose operative parts that engage with the seine may be adjusted to maintain them in a horizontal plane irrespective of any heeling of the vessel while sailing with the wind on either beam.

25 A further object of my invention is to provide a seine puller which, in its operation, shall exert an equal strain on all transverse parts of a seine as said seine is being pulled on board the vessel and which shall act rapidly to deposit said seine upon its platform in such manner that it may be manually folded into a compact form without entangling its parts.

I accomplish these objects by devices 35 illustrated in the accompanying drawings, wherein—

Figure 1 is a plan view of one form of a seine puller which embodies my invention;

Fig. 2 is a view of the same in elevation 40 of its intake end which is normally disposed to face after portions of a vessel during operations of pulling a seine inboard;

Fig. 3 is an enlarged view of the same in 45 vertical section on broken line 3, 3 of Fig. 2;

Fig. 4 is an enlarged view of the same on broken line 4, 4 of Fig. 2;

Fig. 5 is a fragmentary view in vertical section of details of the same on broken line 50 5, 5 of Fig. 1;

Fig. 6 is a fragmentary view of details of the same in vertical section on broken line 6, 6 of Fig. 4;

Fig. 7 is a fragmentary view of the same

in horizontal section on broken line 7, 7 of Fig. 3;

Fig. 8 is a fragmentary view of parts of the same in vertical section on broken line 8, 8 of Fig. 3;

Fig. 9 is a view of details of the same in 60 vertical section on broken line 9, 9 of Fig. 7;

Fig. 10 is a fragmentary view of details of the same in vertical section on broken line 10, 10 of Fig. 4;

Fig. 11 is a fragmentary view of parts of 65 the same in vertical section on broken line 11, 11 of Fig. 4; and

Fig. 12 is a fragmentary view in vertical section on broken line 12, 12 of Fig. 11.

Referring to the drawings, throughout 70 which like reference numerals indicate like parts, as shown in Fig. 2, 13 designates the deck of a fishing vessel within which is fixed a flanged tubular socket 14 whose flange 15 rests upon said deck 13 and which is provided with a lower portion that projects downwardly through said deck 13 and with an upper portion which projects upwardly into and through a flanged plate 16 which is fastened to the under side of the central 75 portion of a platform 17 thus pivotally to support said platform and adapt it to be rotatively movable in a plane parallel with the surface of said deck 13 in a well known manner.

Secured to the top surface of said platform 17 is gear housing 18 whose base plate 19 is provided with a hole which is disposed concentrically with the hole through the flanged socket 14, which two holes jointly 80 serve as a bearing for a vertically disposed driving shaft 20 to whose upper end portion (within the housing 18) is fastened a bevelled gearwheel 38, and whose lower end portion (beneath the deck 13) is assumed to 85 be connected with a controllable means (not shown) for revolving said shaft 20 at times required.

As shown in Fig. 1, the platform 17 is narrower at one edge portion and wider at 100 the opposite edge portion, and during the operation of pulling a seine inboard said seine will act on the seine puller to cause its said platform 17 to be disposed with said narrower edge portion facing some point 105 that is abaft a line drawn athwart the vessel through the axis of the vertical shaft 20, thus said narrower edge portion of said

platform constitutes the after portion thereof.

Rigidly fastened to the top surface of the after portion of the platform 17 are four frame supporting bases 21, 22, 23 and 24 each of which is provided with an inwardly projecting lug, as lugs 25, 26, 27 and 28, respectively.

The lugs 25 and 27 are rigidly connected 10 by a base rail 29, and the lugs 26 and 28 are likewise connected by a base rail 30 which base rails 29 and 30 are preferably made of iron pipe.

The bases 21 and 22 are rigidly connected 15 by a base rail 31 and the bases 23 and 24 are rigidly connected by a base rail 32, both of which base rails 31 and 32 are preferably made of iron pipe.

The supporting base 21 is of larger dimensions than the supporting bases 22, 23 and 24, and is provided with an integral lug 33 disposed to project therefrom with its axis extending in a line that intersects the vertical axis of the shaft 20.

25 The supporting base 21 is hollow and the lug 33 is provided with a concentrically disposed hole extending therethrough from the interior of said base 21, which hole serves as a bearing for a shaft 34 rotatably disposed 30 therein and upon the end portion of the shaft 34 within the interior of the base 21 is fixed a beveled gearwheel 35.

The shaft 34 extends from the interior of the base 21 through the lug 33 and through 35 a pipe 36 into the housing 18, where its end portion is provided with a beveled gearwheel 37 whose teeth are adapted operatively to engage with the teeth of the beveled gearwheel 38, whereby the gearwheel 35 40 may be rotated in response to rotations of the vertical shaft 20.

The pipe 36 rigidly unites the lug 33 with the housing 18 and within its end adjacent to said housing 18 is provided a bearing 39 for the adjacent end of the shaft 34.

Rigidly fixed within the top portion of the base 21 is the lower end of a pipe 40, and fixed within the base 22 is the lower end of a smaller pipe 41, both of which pipes 50 for a like distance extend obliquely upward in parallel with each other to incline inwardly to a slight degree, and the top ends of both pipes 40 and 41 are provided with elbows 42 and 43 respectively, which are 55 rigidly connected with each other by a pipe 44, whereby a rectangular side frame is formed by the pipes 31, 40, 41 and 44.

In the upper end of each of the pipes 40 and 41 is fixed a shaft-bearing block, as 60 bearing blocks 45 and 46; and in the base 22 is a shaft-bearing for the lower end of a shaft 48 which is rotatably disposed within the pipe 41 to extend upwardly from said base 22 to and through the bearing block 46.

65 In the lower end portion of the pipe 40

is fastened a bearing block 49 within which is rotatably journaled a tubular shaft 50 upon the lower end of which is fastened a beveled gearwheel 51 whose teeth operatively engage with the teeth of the beveled gearwheel 35, said tubular shaft 50 being of a length to extend upwardly within the pipe 40 for a distance equal nearly to half of the height of said pipe 40.

Said tubular shaft 50 is provided with a longitudinal slot 52 and slidably mounted on said tubular shaft 50 is a sleeve 53 which is provided with a feather key 54 that projects into said slot 52 whereby the sleeve 53 may not rotatively move on said tubular shaft 50 but whereby it may slidably move in lengthwise directions thereon.

The upper end of the sleeve 53 is provided with an integral beveled gearwheel 55.

The sleeve 53 is rotatably disposed in a bearing 56 that is fastened within the lower end of a tube 57 which is slidably disposed within the pipe 40.

Within the upper end of the vertically 90 slide tube 57 is fastened a screw-threaded nut 58 through which is screwed the screw-threaded portion of a shaft 47 whose upper end portion is journaled in the bearing block 45, as shown more clearly in Fig. 3, and upon the upper end portion of said shaft 47 95 is fastened a beveled gearwheel 59, vertical movements of said shaft 47 being prevented by a collar 60 and the hub of said beveled gearwheel 59.

Upon the top end portion of the shaft 48, 100 within the elbow 43, is fastened a beveled gearwheel 61.

Extending through the pipe 44 is a shaft 62 which is journaled in bearing blocks 63 and 64, and fastened to said shaft 62 are 105 beveled gearwheels 65 and 66 which operatively engage respectively with beveled gearwheels 59 and 61.

That end of the shaft 62, adjacent to the center of a hole 67 formed through the wall 110 of the elbow 42, is made of square cross-section and upon such squared end portion may be disposed a removable crank, like the crank 68, by the manipulation of which crank 68 the shaft 62 may be rotated to cause the vertical shafts 47 and 48 to be simultaneously rotated in opposite directions in an obvious manner.

Both of the pipes 40 and 41, in positions directly opposite each other, are provided 120 each with a vertical slotted opening, as openings 69 and 70 respectively.

Surrounding each of the pipes 40 and 41 is a sleeve, as sleeves 71 and 72 respectively, both of said sleeves 71 and 72 being adapted 125 to be slidably movable in vertical directions on the pipes 40 and 41.

Integral with the sleeve 71 is a boss 73, which projects from its side in a direction toward the pipe 41, and through said boss 130

73 is bored a hole to serve as a journal bearing.

The sleeve 71 is fastened rigidly to the lower part of the tube 57 by screws 74 which extend through said sleeve 71 at a point adjacent to the boss 73 and through the slotted opening 69 and thence into the wall of said tube 57, there being interposed between the wall of the sleeve 71 and the wall of the tube 57 spacing blocks 75, which spacing blocks engage with the edge surfaces of the slotted opening 69, thereby to prevent the tube 57 from having any tendency to rotate when the tubular shaft 50 is rotated.

The sleeve 72 is also provided with a similar boss 76 which directly faces the boss 74 and said boss 76 is also provided with a hole bored therethrough to serve as a journal bearing.

Within the pipe 41 is a nut 77, of cylindrical form, through which is screwed a screw-threaded portion of the shaft 48 and the sleeve 72 is rigidly connected with said cylindrical nut 77 by screws 78 in the same manner that the sleeve 71 is rigidly connected to the tube 57.

One of the screw-threads of the shafts 47 and 48 is right handed while the other 30 one thereof is left handed; thus, when the shaft 62 is rotated by the crank 68 the tube 57 with its attached sleeve 71 and the cylindrical nut 77 with its attached sleeve 72 will be simultaneously moved in the same vertical direction to dispose them at a desired elevation on the pipes 40 and 41.

Disposed to be rotatively movable in the journal bearings formed by the bosses 73 and 76 are the opposite end journals of a 40 roller supporting bracket 79.

Rigidly fixed in the supporting bases 23 and 24 are pipes 80 and 81, respectively, whose top ends are rigidly united by elbows 82 and 83 and a pipe 84 thus to form a side 45 frame corresponding to the side frame formed by the supporting bases 21 and 22, the base rail 31, and top side rail 44.

Within each of the pipes 80 and 81 is rotatably mounted a shaft, as shafts 85 and 86 respectively, each having a screw-threaded portion which extends through a cylindrical nut, as nuts 87 and 88, respectively, which slidably fits within the respective pipe.

Upon the top end portions of each of the shafts 85 and 86 are beveled gearwheels 89 and 90 which operatively engage with beveled gearwheels 91 and 92 respectively, that are mounted on a shaft 93 which extends through the pipe 84, said shaft 93 being provided with a squared end portion 94 to which access may be gained through a hole 95 that extends through the wall of the elbow 82.

The squared end portion 94 of the shaft 85 93 is adapted to receive a crank, like the

crank 68 shown in Fig. 3, whereby the shaft 93 may be rotated to cause the shafts 85 and 86 to revolve thereby simultaneously to raise and lower the nuts 87 and 88 to a desired position within the pipes 80 and 81, the screw-threads on the shafts 85 and 86 being one right handed and the other left handed.

Opposite portions of the pipes 80 and 81 are provided with slotted openings 96 and 97, respectively, and surrounding each of 75 said pipes 80 and 81 are sleeves 98 and 99 having integral bosses 100 and 101, respectively, which are bored to form journal bearings and said sleeves 98 and 99 are rigidly secured to the nuts 87 and 88, respectively, by screws 102 which project through the slots 96 and 97 into the nuts 87 and 88, respectively; there being provided oblong spacing blocks 103 and 104, respectively, which slidably engage with the edges of 85 the slotted openings 96 and 97 respectively.

Within the journal bearings formed in the bosses 100 and 101 are disposed the opposite end journals 105 and 106 of a roller supporting bracket 107 that is adapted to be 90 swingingly movable like the oppositely disposed roller supporting bracket 79.

The roller supporting bracket 79 is bored throughout its length between and through its journals to form a space within which 95 is rotatably mounted a shaft 108, one end portion of which projects within the tube 57 through a hole formed in the slotted portion of the pipe 40 and in the wall of said tube 57, and on said end portion is 100 fastened a beveled gearwheel 109 which operatively engages with the gearwheel 55 of the sleeve 53.

The shaft 108 is provided with two worm gears 110 and 111, respectively, spaced from each other, and directly above each of said worm screws 110 and 111, the roller supporting bracket is provided with an upwardly projecting hollow lug, as lugs 112 and 113 within each of which is a worm 110 gearwheel (as worm gearwheels 114 and 115 respectively) whose periphery projects through an opening that extends from the interior of the lug into the space within which is disposed the shaft 108 operatively 115 to engage with the adjacent one of the worm screws 110 and 111.

The worm gearwheel 114, as more clearly shown in Fig. 8, is integral with an inwardly projecting hub 116 which is rotatably mounted on a fixed shaft 117 one of whose ends is fastened by a nut 118 to the lug 112 to extend therefrom to a lug 119 that projects upwardly from the opposite roller supporting bracket 107, into which 125 lug 119 the other end of said fixed shaft is screwed.

Adjacent to the annular end surface of the hub 116 is a collar 120 and slidably mounted on said hub 116 and said collar 120 130

is a sleeve-like member 121 which is prevented from rotatively moving around the hub 116 by a feather 122 which slidely moves into a slot 123 that is provided in the hub 116, whereby such clutch member 121 may be slidely moved in a lengthwise direction of the shaft 117 and always be revolved in response to a rotation of the worm gearwheel 114.

10 Freely mounted on the fixed shaft 117 is a roller 124, of the form shown more clearly in Fig. 8, within that end of the roller 124 adjacent to the lug 112 is a clutch member 125 which is engaged by the clutch member 121 when said clutch member 121 is moved for a sufficient distance in a direction away from the adjacent side of the worm gearwheel 114, and which is disengaged from the clutch member 121, when such clutch member 121 is moved to the farthest extent toward the side surface of said worm gearwheel 114.

Freely mounted on the sleeve-like clutch member 121 is an externally screw-threaded sleeve 126 which is disposed to engage with an internally screw-threaded flanged portion of the lug 112, said screw-threads being quadruple and of a coarse pitch whereby when said sleeve is rotatively moved for a short distance it will move the clutch member 121 for a sufficient distance to engage it with or disengage it from the clutch member 125.

Extending through the wall of the hollow lug 112, is a spirally disposed slot 127 and fixed in the externally screw-threaded sleeve 126 is an arm 128 which projects outwardly through said slot 127, which arm 128 may be actuated to rotate the sleeve 126 to clutch 40 and unclutch the clutch member 121 in an obvious manner.

Associated with the hollow lugs 113 and the worm gearwheel 115 therewithin, and with an upwardly projecting lug 129 on the roller supporting bracket 107, are also a like clutch mechanism, a like shaft 158 and a like roller 130, a like arm 131, and a like slot 132, all having a like mode of operation, and therefore need not be further described 50 herein.

Projecting downwardly from the roller bearing bracket 107 at points directly beneath the lugs 119 and 129, respectively, are two lugs 133 and 134, as shown more clearly 55 in Fig. 4, within whose lower end portions is pivotally mounted a roller bearing bracket 135.

Extending upwardly from the central portion of the roller bearing bracket 135 is 60 a curved arm 136 to the upper end of which is articulated a lever 137.

Extending downwardly through the lugs 119 and into the lug 133 is a socket hole 138 indicated by dotted lines in Fig. 4 and by 65 full lines in Fig. 8, within which hole 138 is

slidably disposed a fulcrum rod 139 whose upper end is rigidly attached to an elbow 140 which is articulated with the lever 137 at a point not far from the center of its length.

The journal of the elbow 140 within its bearing in the lever 137 is provided with detent recesses 141 and 142 and within the lever 137 extending from the bearing of the elbow 140 to and out of its upper end is a hole within which is disposed a detent rod 143 that is provided with a helical spring 144 that tends to force the inner end of the detent rod 143 into either of the detent recesses 141 and 142.

Normally the lever 137 is in a vertical position with the end of detent rod 143 projected into the detent recess 142, but if it be desired to force the curved arm 136 outwardly to a position shown by dotted lines in Fig. 2, then the detent rod 143 is raised to disengage its end from the detent recess 142, whereupon the lever 137 is forced to the position, indicated by dotted lines in Fig. 2, in which position the detent rod 143 will project its end into the detent recess 141 to lock the parts in their positions shown by said dotted lines.

Rigidly fixed in the roller bearing bracket 135 is a shaft 145 which is disposed normally with its axis in a horizontal plane lower than the plane of the axes of the shafts 117 and 129 and in a vertical plane that is midway between the vertical planes of said shafts 117 and 129, as indicated in Fig. 9, said shafts 100 being extended to a downwardly projecting portion 146 of the oppositely disposed roller bearing bracket 79 which portion 146 is provided with a lug 147 formed to serve as an end support for said shaft 145, as shown 105 more clearly in Fig. 11, said shaft 145 being disposed normally to rest on said lug 147 where it may be releasably locked by a locking member 148 that is rotatably disposed to extend through said downwardly projecting 110 portion 146.

Mounted on said shaft 145 freely to rotate thereon is an idler roller 149.

As shown in Fig. 6, the bearing in the boss 101 of the sleeve 99 (within which is disposed the journal 106 of the roller bearing bracket 107) is of oblong form in cross-section to permit sidewise movements of the journal 106 when the roller bearing brackets 107 and 79 are raised to dispose them 115 in different horizontal planes to compensate for the heeling of the vessel, thus to maintain all three of the rollers 124, 130 and 149 with their axes in a horizontal plane.

In order to aid in supporting the platform 17 in its rotatable position on the deck 13 of a vessel there may be provided a plurality of rollers each mounted in a bracket, like the brackets 150 shown in Fig. 2, all of which brackets are fastened to 125

the deck 13 at equi-distant points in a circle concentric with the shaft 20, in an obvious manner not shown, so that the bottom surface of the platform 17 may engage with 5 and rest upon said rollers.

The operation of my seine puller when constructed in the manner illustrated and described is as follows:

- 10 The platform 17 being rotatably disposed in the deck 13 of the after portion of a vessel, in the manner shown in Figs. 1 and 2, with the operative mechanism abaft the vertical shaft 20, then the end of the seine, that is to be pulled inboard, is lifted from 15 the water and evenly spread over the two rollers 124 and 130, the roller 149 being swung upwardly to the position indicated by dotted lines in Fig. 2 by manipulating the lever 137 in an obvious manner, thus to 20 permit said end portion of said seine to be so disposed, whereupon said lever 137 is manipulated to swing the roller 149 downwardly to dispose the free end portion of its shaft 145 in the lug 147 there to be locked 25 by the locking member 148 so that the axis of said roller 149 will be parallel with the axes of the rollers 124 and 130 and in engagement with the top side of said seine, as indicated in Fig. 9.
- 30 If the vessel be heeling from an even keel the crank 68 is then applied successively to the shafts 62 and 93 which are thereby turned to cause the rollers 124, 130 and 149 to be in a horizontal plane.
- 35 Thereupon the arms 128 and 131 (whose free ends are connected by a link 151) are moved toward the right hand to a position indicated by dotted lines in Fig. 3, thereby to cause the clutch members 121 to engage 40 with the clutch members 125.

Then, rotary motion is communicated to the vertical shaft 20 beneath the deck 13, by any suitable means not shown, which rotary motion will be communicated to the 45 rollers 124 and 130 through the medium of the clutch members 125 and 126, the worm gearwheels 114 and 115, the worm screws 110 and 111, the shaft 108, the bevel gearwheels 109 and 55, the tubular shaft 50, the 50 beveled gearwheels 51 and 35, the shaft 34 and the beveled gearwheels 37 and 38, and the rotary movements of the rollers 124 and 130 will act to draw the seine evenly on to the forward portion of the platform 17, the 55 idler roller 149 acting to cause a tension on the seine to make it forcibly and frictionally engage with the rollers 124 and 130 whose continued rotation will efficiently pull the seine from the water and dispose it on 60 to the platform 17 there to be folded manually by attendants as it is drawn over said rollers 124 and 130.

In order to guide the edges of the seine in the course of its travel over the rollers 65 124 and 130, I have provided four vertical

rollers, like rollers 152 and 153 which are pivotally mounted to extend one between the lugs 25 and a lug 154 that is integral with the elbow 42, another to extend between the lug 26 and a lug 155 that is integral with 70 the elbow 43, another to extend between the lug 27 and a lug 156 that is integral with the elbow 82 and another to extend between the lug 28 and a lug 157 that is integral with the lug 83. 75

Thus, it is obvious that a seine can be pulled inboard by my seine puller from any direction abaft the line drawn athwartship through the axis of the vertical shaft 20 irrespective of the heeling of the vessel 80 either toward the starboard side or toward the port side of said vessel.

Obviously, changes may be made in the forms, dimensions and arrangement of parts of my invention without departing from the 85 spirit thereof.

What I claim is:

1. In a seine puller of the class described, the combination with a seine platform that is adapted to be pivotally mounted on the 90 deck of a vessel to be rotatable in a plane parallel with said deck, of a frame comprising oppositely disposed rectangular side members fastened to said platform and connected together by base rails extending between the lower portions thereof; two vertically adjustable roller supporting brackets pivotally mounted one on each of said side members; two spaced rollers mounted on said roller supporting brackets to extend 95 therebetween with their axes in the same horizontal plane; controllable means for communicating rotary motion to said two rollers; a shaft having one of its ends articulated to one of said roller supporting brackets and adapted to be moved releasably to engage its other end in a locked relation with the other of said roller supporting brackets, in which position its axis is in a vertical plane that is midway between the 100 vertical planes of the axes of said two rollers and in a horizontal plane lower than the horizontal plane of the axes of said two rollers; and an idler roller rotatably mounted 105 on said shaft.

2. A seine puller of the class described, which embodies a seine platform that is adapted to be pivotally mounted on the deck of a vessel to be rotatable in a plane parallel with the surface of said deck; a frame comprising oppositely disposed rectangular side members fastened to said platform and rigidly connected together by base rails extending between the lower portions thereof; seine 110 engaging rollers rotatably associated with said frame; and means for communicating rotary motion to said rollers.

3. A seine puller of the class described embodying a platform, a frame secured to said platform, rollers journaled in said frame, 115

means for changing the height of said rollers, and means for rotating the same.

4. A seine puller of the class described embodying a platform, a frame secured to said platform, rollers journaled in said frame, one of said rollers being pivotally mounted at one end whereby the same may be swung upwardly, means for changing the height of said rollers, and means for rotating the same.

5. A seine puller of the class described embodying a platform, a frame rotatably secured to said platform, three rollers journaled in said frame, the middle roller being pivotally mounted at one end whereby the same may be swung upwardly, means for changing the height of the rollers, means for rotating the two outside rollers, and means for disconnecting the last named rollers from the operating means.

6. A seine puller of the class described embodying a platform, a frame secured to said platform, said frame including spaced rectangular portions rigidly connected at their lower ends, rollers adjustably supported in the vertical legs of the rectangular portions and means for rotating the rollers.

7. A seine puller of the class described embodying a platform, a frame secured to said platform, three rollers journaled in said frame, the middle roller being pivotally mounted at one end whereby the same may be swung upwardly, means for changing the height of the rollers, and means for rotating the two outside rollers.

8. A seine puller of the class described embodying a platform, a frame rotatably secured to said platform, three rollers journaled in said frame, the middle roller being pivotally mounted at one end whereby the same may be swung upwardly, means for changing the height of the rollers, means for rotating the two outside rollers, and means for disconnecting the last named rollers from the operating means.

9. A seine puller of the class described embodying a platform, a frame secured to said platform, said frame including spaced rectangular portions rigidly connected at their lower ends, rollers adjustably supported in the vertical legs of the rectangular portions and means for rotating the rollers.

In witness whereof, I hereinbelow subscribe my name this 30th day of April A. D., 1917.

CHRISTIAN J. BERGLANN.
